UNITED STATES PATENT OFFICE.

J T MERRIMAN JONES, OF HOUSTON, TEXAS.

BUILDING STRUCTURE.

Application filed June 9, 1927. Serial No. 197,707.

The present invention relates to an improved building structure and particularly an improved means for temporarily supporting pans or forms in floor or roof construction of a concrete nature such as are now used in fireproof buildings.

In this improved structure, a steel form, pan or arch is attached to the bottom flange of a steel joist by means of special clips.

10 An important phase of this invention is in the provision of light bar truss joists as reinforcement for concrete, and at the same time acting as a centering and support for steel forms.

15 Another object of importance is to provide novel fastening means on truss joists cooperative with novel concrete forms for supporting the latter in position to form a mold.

20 In this method of construction, only one floor of pans are needed to construct a building of any number of floors since these pans may be removed without, in any way, causing damage or undue strain on the concrete 25 after the concrete has taken its initial set.

An important object of the invention lies in the provision of a structure of this nature which eliminates practically all shoring and the like thereby effecting a large saving in 30 the building construction.

Another very important object of the invention lies in the provision of a structure of this nature which is simple, inexpensive, strong and durable, easy to handle and manipulate, adjustable, thoroughly efficient and reliable, and otherwise well adapted to the purpose for which it is designed. With the above and numerous other objects in view as will appear as the description proceeds, the 35 invention resides in certain novel features of construction, and in the combination and arrangement of parts as will be hereinafter more fully described and claimed.

In the drawing:

40 Figure 1 is a sectional view through a roof or floor showing the features of my invention,

Figure 2 is a perspective view of the pan or core,

45 Figure 3 is a fragmentary side elevation of one form of five piece joist, with expanded web,

Figure 4 is a fragmentary perspective view of another form of joist,

50 Figure 5 is a detail perspective view of one of the clips,

Figure 6 is a section through joist shown in Figure 3,

Figure 7 is the same as Figure 6 except a wedge is used as a means of support, 60

Figure 8 is a section showing in detail the detachable bottom flange for the bar or trussed joist using a cap screw.

Referring to the drawing in detail, it will be seen that the letter (A) denotes one form 65 of the joist structure which is in two, three or five parts, with an expanded web 5 having the narrow top flanges 6 with their edges bent downwardly as at 7 and the wide bottom flanges 8 with their edges bent upwardly 70 as at 9. The webs 5 are expanded in order that the concrete may project therethrough. It will further be noted that top flange 6 is narrower than bottom flange 8.

In Figure 4, another form of the joist has 75 been noted generally by the letter (A), and includes a top bar 11, a bottom flange 12, having its side edges bent upwardly as at 13, and connecting reinforcement 14 of the truss type, and pieces of which are welded 80 or otherwise secured to the bar 11 and along the medium longitudinal dimension of the flange 12.

These joists (A) or (A') will be supported in any desired manner so as to be disposed in parallel spaced relation and to extend horizontally. The letters B denote generally the cores, pans, or arches, each of which comprises a top plate 15 the side edges of which merge into outwardly and downwardly slanting extensions 16 which in turn merge into depending substantially vertical aprons 17 having a plurality of series of apertures 18 disposed vertically therein. 90

The letters F denote the clips each of 95 which is formed from a sheet of metal bent, stamped or cast in the formation clearly shown in Figure 5 so as to provide a body 20, the lower edge of which merges into an oblique extension 21 disposed obtusely thereto and merging into a tongue 22 extending downwardly and in a plane parallel to the plane of the body 20 and offset therefrom. An offset lip 23 is struck from the body 20. An offset lip 24 is formed on the upper end 100 of the body. The ends of the lips 23 and 24 are disposed in substantially the same plane, which plane is parallel and spaced from the plane of the body 20.

After the joist (A) or (A') have been 110 mounted the clips F have their lips 23 and 24 engaged into the desired apertures 18 de-

pending upon the desired depth of the concrete floor or roof joist. After the clips have been set in place in pan, arches, or cores, the cores may be let down so that 5 the tongue 22 engages with the flanges 8 or 12 at their respective extensions 9 or 13 as is clearly illustrated in Figure 1. The concrete is then poured over the pan and the joists in the usual well known manner. After 10 the concrete has set the lips 23 and 24 are cut off by ordinary nippers or like tools and the pans may be readily removed. When desired, suitable lath engaging elements 26 may be mounted as shown in Figure 15 1.

The steel joists will serve as reinforcing for the concrete and also as centering for the steel cores or pans C, thus effecting a large saving. The only shoring necessary 20 will be one shore under the middle of a long span. The absence of forms and shoring will enable the contractor to proceed with the work in a very fast and efficient manner. The floor space will be left clear for the 25 storage of materials and the proper execution of work by the various crafts and sub-contractors.

It is thought that the construction, utility, and advantages of this invention will be quite apparent to those skilled in this art without 30 a more detailed description thereof. The present embodiments of the features of the invention have been disclosed in detail merely by way of example since in actual practice they attain the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages. 35

Having thus described my invention, what I claim as new is:— 40

In combination, a pair of joists each having a flange at the top and bottom thereof, the side edges of the bottom flanges being directed upwardly, a pan positioned between the joists, and means engaged with the pan 50 extending to the inner sides of said side edges and resting on the bottom flange.

In testimony whereof I affix my signature.

J T MERRIMAN JONES.
